UNITED STATES PATENT OFFICE.

WILHELM LORENZ, OF CARLSRUHE, BADEN, GERMANY.

MACHINE FOR CAPPING CARTRIDGES.

SPECIFICATION forming part of Letters Patent No. 274,618, dated March 27, 1883.

Application filed April 19, 1881. (No model.)

To all whom it may concern:

Be it known that I, WILHELM LORENZ, a subject of the Emperor of Germany, residing at Carlsruhe city, in the Grand Duchy of Baden, German Empire, have invented certain new and useful Improvements relating to Machines for Setting Percussion-Caps into Cartridge-Cases, of which the following is a specification.

The accompanying drawings form a part of this specification, and represent what I consider the best means of carrying out the invention.

Figure 1 is a side elevation. Fig. 2 is a vertical section; Fig. 3, an elevation, partly in section, at right angles to that in Fig. 1. Fig. 4 is a plan view, and Fig. 5 represents the post or stand with a portion of a box or vessel into which the capped cartridge-shells are deposited.

Similar letters of reference indicate corresponding parts in all the figures.

The cartridge-cases, into which percussion-caps are to be set, are placed in the channel A, in which they slide or roll automatically to the place for setting. The percussion-caps are placed in the channel B, and slide also automatically by themselves to the said place. The percussion-caps stand upright in the channel B in such a way that in their end position in the steel disk a the opening of the percussion-cap is directed toward the bottom of the cartridge-case b. The cartridge-case lies exactly in the line of the axis of the stamps E and F, Fig. 3, and is kept in this concentric position by the holders c and d, Fig. 2, which latter are pressed on the cartridge-case by the springs c' and d'. The percussion-cap to be set lies in the steel disk a in front of the stamp E, Fig. 3. The operation of the stamps E and F is now such that first the stamp F moves toward the cartridge-case, and the round head f enters into it and presses the same tight on the steel disk a, in which position it remains a short while, according to the peculiar form of the eccentric M. During this time the stamp E presses the percussion-cap which lies in front of the latter into the bottom of the cartridge-case to a certain depth, which is regulated by the nuts h h'. Now acts the cam G, which 50 swings the lever H around its hinge h², thus

causing the angle-lever I to swing, and by means of the connecting-rod K the lower part of the channel A is elevated, swinging around the point a'. This causes the holders d and e to slide off the cartridge-case, which is kept in 55 position by the stamps E and F, and to close in elevated position tight around the following cartridge-case b², which latter hitherto has been kept by the holders S S', which enter the channel A. This latter being lifted has brought 60 the cartridge-case into the dotted position, and the same is now being prepared to undergo the described operation. After this the stamps E and F move backward to release the cartridge-case, in which the percussion-cap is set, 65 and the same falls into the channel C. In the meantime the cam G draws the lower part of the channel A downward into the same position as shown in the drawings, and the cartridge-case b² takes now the position in the axis 70 of the stamps E and F, so that now another percussion-cap, which has slid into its position in the steel disk a, can be set in. The stamp E is moved by the two eccentrics L; the stamp F by the eccentric M, which has its 75 position between the two eccentrics L. The eccentrics operate upon the connecting-rods l and m, which are guided in the bearing-plate, and have at their ends, toward the eccentrics, rollers m', to reduce the friction. The levers 80 N and O swing around the points n and o, and are, with their pulleys m' and rods l and m, continually pressed toward the eccentrics L and M by means of the spring Q.

The arm P bears a piece, p, to serve as guide 85 for the elongation of the stamp F, to force the same to move straight. The spring-disk r is inserted to prevent a deformation of the cartridge-case when the pressure is greater than necessary.

The machine is worked by means of the loose pulley R, and started through the clutch S and the hand-lever. (Not shown.) The whole is placed on a pillar, U, and from all sides free. Under the channel C is a box, V, to receive 95 the finished cartridge-cases.

I claim as my invention—

1. The stamps E F, operating-levers N O, turning on centers o n, connections l m, cams L and M, and spring Q, in combination with 100

each other and with means for supplying cartridge-shells and caps, and for taking away the capped shells, as herein specified.

2. In combination with the channel A, for leading the cartridge-cases into position, and with the cam G, lever H, and connections for operating the channel, the spring-holder c d, adapted to serve as herein specified.

3. In a machine for setting percussion-caps in cartridge-shells, the combination, with the stamps E and F, for holding the shell and pressing in the cap, of the cap-feeding channel B

and shell-feeding channel A, provided with the holders S S', for retaining the shell until the stamps are ready to receive it, as herein set forth.

In testimony whereof I have hereunto set my hand, at Berlin, Prussia, this 1st day of February, 1881, in the presence of two subscribing witnesses.

WILHELM LORENZ.
